United States Patent Office

Des. 210,091
Patented Feb. 6, 1968

210,091

CLOCK OR SIMILAR ARTICLE

Harry L. Laylon, Syracuse, N.Y., and William V. Judson,
Westport, Conn., assignors to General Electric Com-
pany, a corporation of New York

Filed Apr. 17, 1967, Ser. No. 6,735

Term of patent 14 years

(Cl. D42—7)

Fig. 1.

Fig. 2.

Fig. 3.

FIG. 4.

FIG. 1 is a front perspective view of a clock embodying our new design;

FIG. 2 is a top plan view thereof;

FIG. 3 is a front elevational view, it being understood that the border is continuous in the path indicated by the broken lines; and

FIG. 4 is a rear elevational view, it being understood that the border is continuous in the path indicated by the broken lines.

We claim:

The ornamental design for a clock or similar article, substantially as shown and described.
